UNITED STATES PATENT OFFICE.

WILLIAM KLOCKE, OF NEW YORK, N. Y., ASSIGNOR TO PRESSED BEARING COMPANY, INC., OF BROOKLYN, NEW YORK, A CORPORATION OF NEW YORK.

APPARATUS FOR FORMING LINED BUSHINGS.

1,290,578.

Specification of Letters Patent.

Patented Jan. 7, 1919.

Original application filed June 8, 1916, Serial No. 102,518. Divided and this application filed July 21, 1917. Serial No. 182,065.

To all whom it may concern:

Be it known that I, WILLIAM KLOCKE, a citizen of the United States of America, residing in Woodhaven, in the borough of 5 Queens, county of Queens, city and State of New York, have invented certain new and useful Improvements in Apparatus for Forming Lined Bushings, of which the following is a specification.

10 This invention relates to an apparatus for forming lined bushings or the like and aims to provide improvements therein.

The present apparatus is intended to form the lined bushings described in my application Serial No. 102,518, filed June 8, 1916, 15 and the present application is a division of that application.

20 The apparatus of the present invention takes a sheet of composite material, as, for example, a sheet composed of foundation metal such as brass, and lining or bearing metal such as Babbitt metal, and shapes the composite sheet into tubular form.

25 Preferably, the shaping is effected by a curling action, and the shaped tubular body is pressed to render the lining metal dense and relatively homogeneous. A densification of the lining metal is also effected by the curling action, and the relative homogeneity of the densified curled strip is 30 greater than in the case where the sheet is formed into tubular form by a plurality of separate bending operations.

Other features of improvement will be 35 hereinafter set forth.

An embodiment of the invention is illustrated in the accompanying drawings, together with the lined bushing which is produced by the apparatus.

40 In said drawings,—

Figure 1 is a longitudinal section of a lined bushing which is formed by the apparatus;

Fig. 2 is an end view of said bushing;

45 Fig. 3 is a vertical sectional view (on the line 3—3 in Fig. 4) of said embodiment of the apparatus;

Fig. 4 is a vertical section of the parts shown in Fig. 3, the section being at right angles to that in Fig. 3, and along the line 50 4—4 in Fig. 3;

Figs. 5 and 6 are detail sectional views of

the dies illustrated in successive positions of the parts during the process of pressing the bushing to cylindrical shape.

55

In the said drawings I have not illustrated the press construction, as presses adapted for this purpose are well known. The lower or bed die G is provided with guide rods H upon which slides the upper or head die or 60 movable punch I perforated at J to permit the passage of the rods. The die G is provided with an arbor K which is raised above a semi-circular recess L in the die sufficiently to provide a channel M between the arbor 65 and die of semi-circular form and sufficient in depth to permit the passage of the blank or sheet A. The die I has a semi-circular face N adapted in connection with the die face L to complete the formation of the bushing to cylindrical shape around the arbor 70 K. The movable die I is provided with a blank-receiving groove or notch O in the face N forming a shoulder P, and said groove has a depth or radial dimension sub- 75 substantially equal to the thickness of the blank A, and is preferably wider than its depth. The blank A is placed with its lower end in the channel N and with its upper end in the notch O resting against the shoulder P. For 80 the purpose of holding the blank in place I place the same slightly out of plumb. This same result might be accomplished by other means. The blank being held in the position shown in Fig. 3, the upper die is caused 85 to descend and the blank will be forced through the channel M and curled around the arbor K substantially to the point indicated in Fig. 5, which is about as far as it can be forced in such direction. Continued 90 descent of the punch will cause the end of the blank to ride out of the notch O (due to the increasing resistance of the blank as it curls around against the die face N) and the blank will then be forced to cylindrical 95 shape by the die I pressing the blank against the lower die and the intervening arbor K. The curling of the blank or sheet around the arbor acts to densify the lining metal of the composite blank, the densification being pro- 100 gressively greater toward the surface of the liner at the interior of the bushing. This curling action also renders the densification relatively uniform or homogeneous.

The action of the dies and arbor upon the bushing will have the effect of forcing the blank to cylindrical shape and of thoroughly compacting and further densifying the liner, 5 producing a smooth and even surface on the interior thereof which can usually be employed without further treatment. The abutting edges of the blank also retain their closely abutting position and do not separate 10 or spring apart.

Provision is made to permit of a slight movement between the arbor K and the die G in order to thoroughly densify the liner. This may be accomplished in many ways.

15 As shown, it is provided by a yielding support of the arbor. The arbor has a head k which is removably mounted in a standard V suitably attached to the die so as to be removable. The head k is mounted in a bearing 20 in this standard V and is provided with a post W having an enlarged head R which slides in a channel T in the standard. A spring S is mounted in the said channel and is held therein by a threaded plug U by 25 which it is compressed and caused to press upon the head R so as to enable the arbor K to yield under the pressure of the die I.

This yielding mounting of the arbor enables it to give as the blank is forced between it and the die G and avoids pinching the blank in the narrow intervening space, 30 which might result in the buckling of the blank or the stripping from it of the lining metal. It also is important in the final 35 squeezing of the bushing between the dies, since by the yielding of the arbor the die pressures are equalized and the bushing

uniformly compacted. It also assists in the stripping off of the finished bushing.

I have illustrated in the drawings and set forth in the foregoing description the most desirable embodiment of my invention now known to me. It is obvious that numerous modifications may be made therein within the limits of the appended claims.

What I claim is:—

1. An apparatus for the purpose set forth, comprising a pair of dies movable together and having semi-cylindrical faces, and an arbor mounted concentrically within the 50 face of one die with supporting means for the arbor adapted normally to hold it in such concentric position and to yield to pressure exerted between the dies, whereby as the dies come together their pressure against the 55 blank between the dies and mandrel is equalized.

2. An apparatus comprising a pair of dies and an intervening arbor, said dies having curved faces which when closed together embrace the arbor with a parallel intervening space, means for supporting the arbor in normal relation to one of said dies, and the other die having a shoulder formed by a notch in one side of its curved face adapted 65 to bear on an edge of a flat metal blank to push it between the first-named die and arbor, said shoulder being outside the cylindrical faces of the dies when united, so that it releases the end of the blank before the latter is brought to its final form.

In witness whereof, I have hereunto signed my name.

WILLIAM KLOCKE.
